UNITED STATES PATENT OFFICE.

MAHLON L. DUNBAR, OF AKRON, OHIO, ASSIGNOR TO NATHANIEL G. OATTIS, OF AKRON, OHIO.

TWINE-CUTTER.

1,285,075.

Specification of Letters Patent. Patented Nov. 19, 1918.

Application filed July 9, 1917. Serial No. 179,515.

To all whom it may concern:

Be it known that I, MAHLON L. DUNBAR, a citizen of the United States, residing at Akron, in the county of Summit and State of Ohio, have invented new and useful Improvements in Twine-Cutters, of which the following is a specification.

This invention is an improved twine cutter for use on a counter, shelf or the like in a store or ware-house for cutting the twine used in wrapping bundles, the object of the invention being to provide an improved twine cutter of this class in which the cutting blade is so guarded as to render it impossible to cut the fingers thereon; in which the blade may be readily removed and replaced, and to also provide a cutter which may be arranged in a variety of positions, on or under or at one side of a counter, shelf or the like.

The invention consists in the construction, combination and arrangement of devices hereinafter described and claimed.

In the accompanying drawings:—

Fig. 1 is an elevation, partly in section, of a twine cutter constructed and arranged in accordance with my invention.

Fig. 2 is a similar view of the same at right-angles to Fig. 1.

Fig. 3 is a horizontal sectional view of the same, showing the base in plan.

Figs. 4, 5, 6 and 7 are diagrammatic elevations, showing the cutter arranged in different positions on a counter and shelf.

In the embodiment of my invention I provide a holder 1 which comprises a base 2, a standard arm 3 and a head 4. The base is here shown as lozenge shape but may be of any other suitable form and is provided with openings for the reception of screws wherewith to secure the device on or under a counter, shelf or the like. The standard arm is curved. The head 4 is provided with a slit 5 for the reception of a

blade 6. The slit is open at the outer side of the head and the head is provided on its inner side, and at opposite sides of the arm with slots 7 which are open on the inner side of the head and across which the blade extends, the blade being spaced from the ends of the slots and the head hence serving as a guard to prevent the possibility of the finger of the user coming in contact

with and being cut by the edge of the blade. Hence the twine cutter is entirely safe. The 55 blade is here shown as segmental in form and is secured between the sides of the head by a set screw 8. By first removing the set screw the blade can be removed and replaced by another.

In practice I provide a number of blades for use consecutively in connection with the holder so that when one blade becomes dull it can be discarded and another used instead. By the provision of the widened 65 head at the outer end of the arm and the arrangement of the slots 7 therein the blade provides two cutting portions, one above and the other below the arm, either of which can be used at will.

Owing to the construction and form of the holder my improved twine cutter can be arranged in a variety of positions on or under a counter, shelf or the like. In Fig. 4 I show the holder arranged and secured on the upper side of a counter *a*. In Fig. 5 I show the holder arranged on the edge of a counter *b* and extending downwardly. In Fig. 6 I show the holder arranged horizontally on the edge of a counter *c* and extending in one direction in full lines and in the opposite direction in dotted lines. In Fig. 7 I show the twine cutter secured to the under side of a shelf *d* above a counter *e*.

While I have herein shown and described a preferred form of my invention, I would have it understood that changes may be made in the form, proportion and construction of the several parts, without departing 90 from the spirit of my invention and within the scope of the appended claims.

Having thus described my invention, I claim:—

1. A twine cutter comprising a base plate, 95 a curved arm extending from said base plate and terminating in a widened head lying entirely beyond the edges of the base, and a blade disposed within a bifurcation in said head with its cutting edge disposed toward said base, the portions of said head adjacent both edges of the arm being cut away to expose said cutting edge, either edge of said arm serving to guide twine toward said blade.

2. A twine cutter comprising a base plate,

a curved arm extending from said base plate and terminating in a widened head lying entirely beyond the edges of the base plate, and a blade disposed within a bifurcation in said head, with its cutting edge disposed toward said base, the portions of said head adjacent both edges of the arm being cut

away to expose said cutting edge, either edge of said arm serving to guide twine toward said blade, said cutting edge being inclined 10 in respect to said base.

In testimony whereof I affix my signature.

MAHLON L. DUNBAR.
